SIMEON SCHOON JACKSON, OF READVILLE, MASSACHUSETTS, ASSIGNOR TO THE STAFFORD COMPANY, OF READVILLE, MASSACHUSETTS, A CORPORATION OF NEW JERSEY.

WEFT-REPLENISHING LOOM.

1,100,659.

Specification of Letters Patent. Patented June 16, 1914.

Application filed April 21, 1910. Serial No. 556,761.

To all whom it may concern:

Be it known that I, SIMEON SCHOON JACKSON, a subject of Great Britain, residing at Readville, in the county of Norfolk, State of Massachusetts, have invented a certain new and useful Improvement in Weft-Replenishing Looms, of which the following is a specification, reference being had therein to the accompanying drawings.

10 In looms in which replenishment of the working weft-supply is effected automatically, the free ends of the weft-threads carried by the reserve shuttles or weft-carriers contained in the magazine are engaged with

15 a suitable weft-end holder, so that when one of such shuttles or weft-carriers is brought into service in weaving the starting end of the weft-thread carried thereby is held so that it pays out through the delivery eye

20 of the shuttle and is thereby caused to lie in the shed in the warp-threads as the shuttle makes its first flight following the replenishment. In consequence of the starting end being thus engaged, a so-called

25 weft-end remains extending from the weft-end holder to the adjacent selvage of the cloth being woven. This weft-end is or should be parted close to the said selvage, for which purpose a weft-end parter is em-

30 ployed, usually mounted upon the loom-temple at such selvage, and operating to effect the parting by breaking or cutting the weft-end. In looms in which a weft-fork is employed at the same side of the loom,

35 located between the weft-parter and weft-end holder, the weft-fork interferes with the prompt parting of the weft-end. Its tines hold the weft-end back when the first pick of the fresh weft is beaten up, thereby

40 preventing the weft end from entering completely into the grasp of the weft-parter so as to be parted thereby, and also slackening the weft-end so that as a result a number of picks of the shuttle take place before the

45 cloth becomes advanced sufficiently by the taking-up to draw the weft-end into such grasp, delaying thereby the parting of the weft-end.

The object of the invention is to obviate interference by the weft-fork with the prompt parting of the weft-end. In accomplishing this object I construct the weft-

fork at its working face with a recess adjacent its feeler-portions for coacting with the working weft-thread, such recess receiving 55 the outwardly-extending weft-end and affording clearance or relief therefor. Thus, instead of being held back by the weft-fork as usual, the weft-end occupies the clearance-recess, and thereby is permitted to enter 60 into the grasp of the weft-parter at the first beat-up by the lay following replenishment. Hence the weft-parter is enabled to part the weft-end immediately.

Embodiments of the invention are illustrated in the drawings, in which latter,—

Figure 1 shows in plan certain parts of a loom designed to effect replenishment by automatically making change of shuttle, one embodiment of the invention being shown 70 in connection therewith. Fig. 2 is an elevation looking from the right hand side in Fig. 1. Fig. 3 is a side elevation of the weft-fork shown in Figs. 1 and 2 in connection with the other devices. Fig. 4 shows in 75 side elevation a slightly different form of weft-fork.

In Figs. 1 and 2 a portion of cloth is represented at 1, and at 2 are shown portions of the warp-threads extending rearwardly in the loom therefrom. 3, Fig. 1, is a portion of the breast-beam. A loom-temple is shown at 4 in engagement with the selvage-portion of the cloth. At 5 is a weft-fork located adjacent the temple 4, its usual 80 carrying slide being shown at 6 mounted in the guideway 7 on the breast-beam, and a portion of the weft-hammer is represented at 8 in Fig. 1. A magazine for reserve shuttles is shown at 9 at the outer end of the 90 breast-beam, and at 10 is a weft-holder applied to the rear of the said magazine, at its inner end, near the top thereof, it being in the form of a wooden cylinder conveniently fastened to the rear side of the magazine by 95 means of a screw. The starting ends of the weft-threads in the shuttles contained in the magazine are wrapped around the said holder. In the present instance a weft-end guide, shown at 11, is employed in connection with the lower portion of the magazine, it being located just above the open mouth at the base of the magazine through which the shuttle which is being transferred to the 100

lay is carried rearward by the action of the feeding or transferring devices (not shown). This guide consists of a piece of wire fastened by its outer end in a supporting arm 5 11^a, the main length of the wire, constituting the stem of the guide, extending horizontally toward the adjacent side of the loom from the said supporting arm, and the wire being bent at its inner end to form an 10 open loop or hook. As the bottom shuttle of the stack contained within the magazine is transferred from the base of the magazine to the lay, the weft-end extending from the delivery eye of such shuttle to the weft-end 15 holder is carried by the rearward movement of the shuttle against the horizontal stem of the guide, and as the ensuing pick of the shuttle from such end of the lay to the opposite end takes place the weft-end slips in- 20 ward along the stem of the guide, effecting entrance into the eye or loop at the inner end of the guide, where it remains retained. At 12 is a weft-parter mounted on the outer side of the head of the temple. It may be 25 of any desired construction. In the present instance I have shown a parter comprising a cutting blade 12^a, carried by a lever pivoted upon the temple-head, the said lever being acted upon by a contracting spiral 30 spring 12^b which holds the said lever normally in its retracted position, with the cutting blade elevated above a notch in the rear face of the temple-head. The depending portion of the said lever constitutes a 35 tail which in the advance of the lay is struck by the latter, so that the lever shall thereby be turned upon its pivot and the cutting blade moved across the notch of the temple-head.

40 Figs 1 and 2 represent the situation following the first pick after replenishment, a weft-end *a* being shown extending down from the weft-end holder through the eye or loop of the guide 11 and thence past the 45 weft-fork, weft-parter, and temple into the shed, the weft-thread extending obliquely rearward within the shed toward the opposite side of the loom. These figures show the weft-end occupying the recess with which, 50 in accordance with my invention, I construct the weft-fork for the purpose of affording sufficient clearance or relief to the weft-end to permit it to draw forwardly into the grasp of the weft-parter. In Figs. 1 and 2, 55 and in Fig. 3, in which the weft-fork is shown separately, the clearance-recess is provided by bending the tines of the weft-fork downward immediately adjacent the pivotal hub 5^a, and then cranking or bending the 60 same as at 5^a, and then again vertically downward so that the feeler-portions 5^b shall be offset to a considerable extent with reference to the upper portions 5^c and also with reference to the pivotal point or hub 5^a. The

working face of the weft-fork is substantially upright. The weft-clearance recess is thereby formed in the upper portion of the working face of the weft-fork and the tines of the fork extend downward from such recess, forming the feeling portions 5^b for engagement with the working weft-thread in the loom. The weft-end holder and the guide 11 are elevated relatively to the selvage so that the weft-end draws in an upward direction from the selvage to the said 75 guide and holder. Thereby the weft-end is somewhat elevated at the weft-fork and caused to find its way into the clearance-recess. In some cases the guide 11 may be dispensed with and a weft-end holder of any 80 desired character may be located at a lower point than that of its position shown in Fig. 2.

In the form of weft-fork shown in Fig. 4 the tines, instead of being bent directly 85 downward from closely adjacent the pivotal point or hub 5^a, extend rearward a short distance from the said pivotal point or hub and are then bent downwardly, and then are carried in an oblique direction downwardly 90 and forwardly as at 5^c, being then bent or cranked horizontally rearward as at 5^d forming the clearance-recess 5^e, the tines extending downward from the recess so as to form the feeler-portions 5^f.

The form and construction of the weft-fork, and the shape, etc., of the clearance-recess, may be further modified without necessarily involving a departure from the principle of the invention.

I claim as my invention:—

1. In a weft-replenishing loom, in combination, a weft-parter, a weft-end holder, and a weft-fork having its tines bent to form a weft-clearance recess in the upper portion 105 of its working face, with the lower portions thereof extending downward from such recess and forming the feeler-portions for engagement with the working weft-thread in a loom.

2. In a weft-replenishing loom, in combination, a weft-parter, a weft-end holder, and a weft-fork having at the working face thereof a weft-end clearance-recess adjacent its feeler-portions.

3. In a weft-replenishing loom, in combination, a weft-parter, a weft-end holder, and a weft-fork having at the working face thereof an upper weft-end clearance-recess, and feeler-portions extending downward 120 from such recess for engagement with the working weft-thread.

4. In a weft-replenishing loom, in combination, a weft-parter, a relatively-elevated holder for the end of the fresh weft, and a weft-fork pivoted intermediate the said weft-parter and weft-end holder and having tines cranked or bent horizontally at an in-

termediate point in their height so that the
feeling portions of said tines are offset with
relation to upright portions of the tines
above the crank or bend, the recess above the
5 crank or bend receiving the weft-end be-
tween the weft-end holder and the selvage
of the cloth being woven.

In testimony whereof I affix my signature
in presence of two witnesses.

SIMEON SCHOON JACKSON.
